UNITED STATES PATENT OFFICE.

EZRA B. SMITH, OF RAVENSWOOD, ILLINOIS, ASSIGNOR TO JOHN EDWARD OGDEN, OF MOUNTAINVILLE, NEW YORK.

CONTROL MECHANISM FOR DOORS.

Application filed December 11, 1922. Serial No. 606,276.

To all whom it may concern:

Be it known that I, EZRA B. SMITH, a citizen of the United States, and a resident of Ravenswood, county of Cook, Chicago, and State of Illinois, have invented certain new and useful Improvements in Control Mechanism for Doors, of which the following is a specification.

This invention relates to control mechanism for doors and particularly to mechanism for controlling elevator hatchway doors.

One of the objects of the invention is to provide hatchway or fire door control mechanism so constructed and arranged that the doors can not be opened unless the elevator car is opposite the landing where the doors are located and furthermore the opened doors will be automatically closed when the car leaves the landing.

Another object of the invention is to provide latching mechanism for holding the doors open and located as to be normally disposed out of the path of moving parts of the elevator car but adapted to be moved into the path thereof when the doors are opened.

Another object of the invention is to provide hatchway door latching mechanism for holding the doors open and latch releasing means carried by the elevator car, the latching mechanism being disposed out of the path of the latch releasing mechanism unless the doors are latched open.

Another object of the invention is to provide means in connection with elevator hatchway doors for insuring the quiet operation thereof.

Another object of the invention is to provide means operable by the movement of the elevator car in either direction away from a landing for releasing opened hatchway doors.

Further objects of the invention will appear from the following description taken in connection with the drawings which form a part of this application and in which,

Fig. 1 is a sectional elevation of an elevator hatchway showing a plurality of landings and sets of hatchway or fire doors.

Fig. 2 is a sectional elevation of one side of the hatchway shown in Fig. 1.

Fig. 3 is an enlarged elevational view showing the latching mechanism for holding the hatchway doors in open position.

Fig. 4 is a sectional elevation taken substantially on line 4—4 of Fig. 3.

Fig. 5 is a sectional elevation taken substantially on line 5—5 of Fig. 3 and showing particularly the latch releasing means carried by the elevator car.

Fig. 6 is a transverse sectional elevation taken substantially on line 6—6 of Fig. 3, and

Fig. 7 is an enlarged sectional elevation showing the cushioning device for cushioning the closing movement of the door.

The invention briefly described comprises mechanism for latching the hatchway or fire doors open and means operable upon movement of the elevator car away from the landing for releasing said latching mechanism. The latching mechanism is normally disposed out of the path of the releasing means and is movable into operative position as the doors move to open position. In the particular form of the invention shown the means for moving the latching mechanism to operative position consists of yieldable means carried by the door or as illustrated by the lower section of the door. Means has also been provided for cushioning the closing movement of the doors thereby insuring the quiet operation thereof.

Referring to the drawings, there is shown in Figs. 1 and 2 a portion of an elevator hatchway 10 having a plurality of sets of doors A and B located at different floor levels 12 and 13.

In the particular form of the invention shown an upper section 14 and a lower section 15 is provided for each set of doors, these sections being movable toward each other to closed position as shown at A and being movable away from each other to open position as shown at B. A latch 16 is carried by one of the sections, 14, and the other section 15 has a latch engaging member 17. As the doors are moved to closed position as shown at A the latch 16 is automatically swung into latching position.

The hatchway doors may be counterbalanced in any suitable manner and one satisfactory arrangement consists in making the upper section 14 heavier than the lower section 15 so that when the sections are released after having been latched in open position they will automatically close. The two doors of each set are connected by a ca-

ble 18 secured to the lower edge of the upper section as shown at 19 and to a bracket secured to the upper edge of the lower section as shown at 20. The intermediate portion of the cable 18 passes over a sheave 21 mounted in the hatchway on a fixed support.

It is desirable that only one pair of doors or door sections be opened at one time and in Fig. 1 the sections B are shown as open 10 and the sections A as closed. It will be obvious that the upper section B will prevent the lower section A from opening and the lower section B will prevent the upper section 15 of the doors located below the landing 13 from opening.

When hatchway doors of the type described are located in hotels, office buildings, etc., it is very desirable to insure the quiet operation. This is accomplished in the present invention by means of an air check device shown in Fig. 7 and consisting of a cylinder 30 secured by a bracket 31 to the door guides in the hatchway adjacent each 20 set of door sections (see also Fig. 1) and a piston 32 having a piston rod 33 extending through one end of the cylinder and provided at its lower end with an abutment member or striking disc 34. The disc 34 is adapted to be engaged by the bracket 20 25 carried at the upper end of the lower door section as the sections approach each other or as the lower section is raised.

The piston as shown in Fig. 7 has constricted openings 35 therethrough and above 30 the piston there is slidably mounted upon an extension 36 of the piston rod a floating washer 37, the upward movement of this washer on the extension 36 being limited by a fixed or riveted washer 38. The opposite end of the cylinder 30 has formed there- 35 in constricted openings or leakage openings 39. The air check operates as follows. When the doors are opened the piston will drop in the cylinder, the air within the cylinder escaping through the openings 39. When the doors are closed the bracket 20 on the lower door section will engage the abutment or striking head 34 on the piston rod 33 and will force the piston head 32 40 upwardly in the cylinder 30. During this operation the washer 37 will close the openings 35 in the piston head and the piston head will therefore compress the air in the cylinder positioned above the head sufficiently to check the upward movement of 45 the lower section. After the door has been completely closed and there is no further pressure against the piston rod the compressed air between the piston head and the cylinder head will escape gradually through a screw valve 40 mounted in the upper end 50 of the cylinder. This valve has an inclined opening 41 therein and the screw may be adjusted to regulate the escape of the air.

65 In this way various sizes of doors may be

handled by the air check device without changing the dimensions of the parts.

The mechanism for locking the door sections in open position will next be described. In the form of the invention illustrated, this mechanism acts in conjunction with the descending or lower section of the door although if desired it could be adapted to coact with the upper section.

Referring particularly to Fig. 3 the locking mechanism is carried by a disc 50 eccentrically pivoted at 51 to a fixed pivot located in the hatchway at one side of the path of travel of the elevator and the hatchway doors. The arm 52 is fixedly secured 75 to the disc 51 and extends upwardly therefrom and this arm carries at its upper end a pivoted latching pawl 53. The pawl 53 is actuated on its pivot in a clockwise direction by spring 54 and is limited in this 80 movement by a stop 55 formed on the pawl and engageable with the arm 52.

As clearly illustrated in Fig. 1 adjacent the floor level 12 the mechanism for latching the doors open is normally disposed at 90 an angle to the vertical and in such a position that the unlatching mechanism or releasing mechanism carried by the elevator car and hereinafter described, will not engage the latching mechanism unless the door 95 sections controlled thereby are latched in open position.

When, however, the car stops at a landing or floor level and the doors are open, the latching mechanism will be swung to 100 the position shown at the bottom of Fig. 1 or to operative position in the following manner. Each lower section of the hatchway doors has secured to one edge a resilient strip 56 engageable with a stud or roller 57 mounted on the disc 50 as the lower section approaches its open position. The engagement of the strip 56 with the roller or stud 57 will swing the disc 50 about its pivot in an anticlockwise direction thereby swinging the arm 52 to substantially vertical position in which the spring pressed pawl 53 will be engaged by and will subsequently snap back over a bracket 58 secured to the lateral edge of the lower or descending door section. A stop lug 59 is located in the hatchway to form a limit for the downward movement of the section 15, this lug being disposed in the path of the bracket 58.

In order to insure the correct positioning of the latching mechanism, a headed pin or stud 60 is fixedly secured in the hatchway and is positioned in an arcuate slot or notch 61 formed in the disc 50. This stud or pin positively limits the movement of the disc in both directions and the head on the stud tends to retain the disc in position and to confine the disc to its movement of oscillation about the pivot 51.

Means is provided for insuring the release of the hatchway doors when the elevator car leaves the floor level thereby insuring the closing of these doors. This means comprises a pair of tripping rollers or studs 62 carried by the elevator platform and adapted to engage a stud 63 extending laterally from the pivot of the latch 53. When the car ascends from the floor level the lower stud or roller 62 will engage the stud 63 carried by the latch and when the car descends the upper roller will perform this function. It will be evident therefore that the latch will be swung away from engagement with the bracket 58 when the car ascends or descends from the floor level. Upon the release of the door sections in case the upper section is heavier than the lower section the door will be closed by gravity and the latch 16 will latch the door in closed position.

The hatchway doors are opened and closed in the following manner. When the elevator operator reaches a floor level and desires to open the doors he releases the latch 16 and manually forces the door sections apart. When the lower section approaches its wide open position he may if desired place his foot upon the upper edge thereof thereby forcing this section to wide open position. During this operation the resilient strip 56 will swing the latching mechanism to operative position about this pivot 51 and the latch 53 will snap over the bracket 58 carried by the door section. When the operator applies power to the car and the car moves away from the floor level in either direction the latching mechanism will be swung to in-operative position by one of the rollers or studs 62 whereupon the doors will again move to closed position.

In connection with the invention just described there has been shown means for automatically unlatching the door latching mechanism in case of fire. This mechanism has not been illustrated in detail nor will it be described in detail since it forms the subject matter of another application. This automatic releasing mechanism comprises a weight 70 carried by a chain 71 the opposite end of which is connected to one end of a fusible link 72. The other end of the link 72 is connected by a chain 73 to a fixed support 74. Also a chain 75 connects the two ends of the link 72 and is normally slack as shown in Fig. 1. The downward movement of the weight 70 is limited by a stud 76 fixedly secured in the hatchway and disposed in an elongated slot 77 formed in the weight. The release of the latch by the weight is accomplished through a lug 78 carried by the weight adjacent the upper end thereof and projecting laterally therefrom. The lug 78 is so located with reference to an arm 79 secured to the disc 50 that

the downward movement of the weight 70 after its release will cause the lug 78 to engage the arm 79 and thereby swing the disc 50 about its pivot 51 moving the latch 53 out of engagement with the bracket 58 carried by the lower door section. It will thus be seen that when a fire causes a dangerous rise in temperature in the hatchway the fusible link will be melted thereby releasing the weight and permitting the weight 70 to release the latching mechanism. The doors will thereafter be automatically closed.

From the foregoing specification it will be seen that a simple practical and effective means has been provided for latching hatchway doors in open position and that this latching mechanism will be automatically released by the movement of the elevator car away from the floor level. Furthermore by means of the air check device the closing movement of the door sections will be cushioned thereby insuring the quiet operation thereof.

Although one specific embodiment of the invention has been particularly shown and described, it will be understood that the invention is capable of modification and that changes in the construction and in the arrangement of the various cooperating parts may be made without departing from the spirit or scope of the invention as expressed in the following claims.

What I claim is:

1. In combination, an elevator car a movable hatchway door biased to close, normally inoperative mechanism disposed out of the path of movement of the elevator car for latching said door in open position and means for moving said latching mechanism to operative position.

2. In combination, a movable hatchway door biased to close, normally inoperative mechanism for latching said door in open position and means on the door for moving said latching mechanism to operative position.

3. In combination, a movable hatchway door biased to close, normally inoperative mechanism for latching said door in open position and means on the door engageable with said latching means during the door opening movement for moving said latching mechanism to operative position.

4. In combination, a movable hatchway door biased to close, normally inoperative mechanism for latching said door in open position and yieldable means normally out of engagement with the latching mechanism for moving said latching mechanism to operative position.

5. In combination, a movable hatchway door biased to close, normally inoperative mechanism for latching said door in open position and resilient means normally out

of engagement with the latching mechanism for moving said latching mechanism to operative position.

6. In combination, a movable hatchway door biased to close, normally inoperative mechanism for latching said door in open position and yieldable means on the door for moving said latching mechanism to operative position.

10 7. In combination, a movable hatchway door biased to close, normally inoperative mechanism for latching said door in open position and resilient means engageable with said latching means during the door 15 opening movement for moving said latching mechanism to operative position.

8. In combination, a movable hatchway door biased to close, normally inoperative mechanism for latching said door in open 20 position, means for moving said latching mechanism to operative position, an elevator car, and means carried by the car for releasing said latching means from the door.

25 9. In combination, a movable hatchway door biased to close, normally inoperative mechanism for latching said door in open position, means for moving said latching mechanism to operative position, an elevator car, and means carried by the car and operable as the car leaves the landing for releasing said latching means from the door.

30 10. In combination, a movable hatchway door, an elevator car, normally inoperable door latching mechanism normally disposed out of the path of movement of the elevator car, yieldable means for moving said mechanism to operative position and means carried by the car for releasing said latching mechanism from the door.

35 11. In combination, a movable hatchway door, an elevator car, normally inoperable door latching mechanism, yieldable means 45 carried by the door for moving said mechanism to operative position and means carried by the car for releasing said latching mechanism from the door.

40 12. In combination, a movable hatchway door, an elevator car, normally inoperable door latching mechanism, yieldable means for moving said mechanism to operative position and means carried by the car and operable as the car leaves the landing for 55 releasing said latching mechanism from the door.

45 13. In combination, a plurality of movable hatchway door sections adapted to move toward each other to closed position and means including a cylinder and a weighted piston movable by gravity to operative position for cushioning the closing movement of the doors as they approach each other.

50 14. In combination, a plurality of mov-

able hatchway door sections adapted to move toward each other to closed position and means including a pneumatic cylinder and a piston therein mounted in the hatchway and engageable by one of the doors for cushioning the closing movement of said doors as they approach each other, the piston being weighted to return to operative position after the operation thereof.

75 15. In combination, a plurality of movable hatchway door sections adapted to move toward each other to closed position and means including a pneumatic device mounted on a fixed support and engageable by one of the doors for cushioning the closing movement of said doors as they approach each other, said pneumatic device including a piston so weighted as to return by gravity to operative position after the cushioning movement thereof.

80 16. In combination, an elevator car, a plurality of movable hatchway door sections biased to close, normally inoperative mechanism disposed out of the path of movement of the elevator car for latching 85 said doors in open position and means for moving said latching mechanism to operative position.

17. In combination, a plurality of movable hatchway door sections biased to close, normally inoperative mechanism for latching said sections in open position and means carried by one of the sections for moving 90 said mechanism to operative position.

100 18. In combination, vertically movable 100 hatchway door sections biased to close, normally inoperative mechanism for latching said sections in open position and yieldable means carried by one of the sections for moving said mechanism to operative position.

105 19. In combination, vertically movable upper and lower hatchway door sections biased to close, normally inoperative mechanism for latching said sections in open 110 position and means carried by one of the sections for moving said mechanism to operative position.

115 20. In combination, vertically movable upper and lower hatchway door sections biased to close, normally inoperative mechanism for latching said sections in open position and means carried by the lower section for moving said mechanism to operative position.

120 21. In combination, vertically movable upper and lower hatchway door sections biased to close, operative connections between said sections, normally inoperative mechanism engageable with the lower section, for latching said sections in open position and means carried by one of the sections for moving said mechanism to operative position.

125 22. In combination, a vertically movable

- door, latching mechanism for said door, said mechanism including an eccentrically pivoted member having its center of gravity so located as to swing the latch to inoperative 5 position and means engageable with said member to swing the latch to operative position as the door is opened.
23. In combination, a vertically movable door, latching mechanism for said door, 10 said mechanism including an eccentrically pivoted member having its center of gravity so located as to swing the latch to inoperative position and means on the door engageable with said member to swing the latch to operative position as the door is opened.
24. In combination, a vertically movable door, latching mechanism for said door, 15 said mechanism including an eccentrically pivoted member having its center of gravity so located as to swing the latch to inopera-
- tive position and yieldable means engageable with said member to swing the latch to operative position as the door is opened.
25. In combination, a movable hatchway door, an elevator car, normally inoperable door latching mechanism disposed out of the path of movement of the car, and means for moving said latching mechanism to operative position. 25
26. In combination, a movable hatchway door, an elevator car, normally inoperable door latching mechanism disposed out of the path of movement of the car, and means on the hatchway door for moving said latching mechanism to operative position. 30 35

In witness whereof, I have hereunto set my hand this 7th day of December, 1922.

EZRA B. SMITH.

Witness:

I. B. MOORE.
